UNITED STATES PATENT OFFICE.

JAMES W. MORRIS, OF OAKLAND, CALIFORNIA, ASSIGNOR OF ONE-HALF TO RICHARD W. SWEET, OF OAKLAND, CALIFORNIA.

BROODER.

1,078,547.

Specification of Letters Patent.

Patented Nov. 11, 1913.

Application filed April 18, 1912. Serial No. 691,624.

To all whom it may concern:

Be it known that I, JAMES W. MORRIS, citizen of the United States, residing at Oakland, in the county of Alameda and State of California, have invented certain new and useful Improvements in Brooders, of which the following is a specification.

My present invention relates to brooders for chicks, which comprises a suitable compartment with a suspended blanket for snugly covering the chicks during the brooding period and also providing a limited area where the chicks may have access to when such is desired.

15 The principal objects of my invention are to provide a brooder which is simple in construction, efficient in action, and inexpensive in manufacture.

Further objects of my invention are to 20 provide for proper ventilation of the brooding compartment; to render the ventilating means regulatable, and to enable the device to be adapted for comfortably receiving the chicks according to their size.

25 In the drawing, forming a part of this specification: Figure 1 is a perspective view of the brooder, parts being broken away and removed to disclose details of construction. Fig. 2 is a central vertical longitudinal, sectional view of the brooder embodying my invention. Fig. 3 is a top plan view of what I hereinafter term the "hover." Fig. 4 is a cross sectional view on lines 4—4 of Fig. 2.

Similar characters refer to similar parts 35 throughout the several views.

The outer housing 1, preferably made of corrugated paper board, comprises a box-like portion 2, open at the top and having an opening 3 at one side thereof, and a second box-like portion 4 open at the top and one side and adapted to telescope the portion 1. The sides adjacent the open end of portion 4 are braced at the top by a tie piece 5 and when the parts 2 and 4 are in 40 assembled relation to each other, the opening 3 communicates with the interior of the box-like portion 4, as clearly shown in Fig. 1 of the drawing. As a means to protect the occupants of the brooder from rodents, 45 hawks, or the like, I prefer to cover the open tops of portions 2 and 4 with pieces of wire netting 6 and 7, respectively, so disposed or connected therewith as to be readily detachable to permit access to the interior of 50 the housing, when such is found necessary.

The brooding compartment 8, hereinafter termed hover, comprises an outer cylindrical shell 9 provided with a bottom 10; an inner cylindrical shell 11 provided with a top 12, having an opening 13 centrally thereof, the shell 11 being relatively smaller than shell 9 permitting the one to telescope the other and providing an air space 14 therebetween; a ventilating stack 15 passing through the opening 13 and held in a rigid position with shell 11 through brace rods 16 or their equivalents, the stack being disposed with its lower end in spaced apart relation to the bottom 10 when the shells 9 and 11 are in assembled relation to each other; a guard 17 about the lower end of the stack 15, and a pad or blanket 18 suspended from top 12. The said pad or blanket 18, snugly engages the chicks, is preferably annular in shape, disposed about stack 15, and is preferably formed of one piece in order that the chicks will not become entangled therein. The shells 9 and 11, have openings 19 and 20, respectively, which may be made to register, to permit access to and from the hover, or the latter shell may be moved to vary or close the opening, and when assembled, the hover is positioned with shell 9 partly extending through opening 3, and the opening 19 therein permits access to and from the area provided for by box-like portions 4 of the house.

The lower margin of shell 11 has a plurality of recesses 21 therein, which permit the air to find egress to the hover through space 14 and recesses 21, the foul air finding egress through stack 15. Inasmuch as the opening of stack 15 is adjacent the bottom of the hover, it provides for constant renewal of the fresh air into the compartment.

The operation of the device is as follows: During the day, the device is arranged as shown in Fig. 1, with shell 11 turned so that its aperture 20 permits access to and from the area formed by housing portion 4, through opening 19. At night time, with all the chicks within the hover, the shell 11 is rotated sufficiently to close the opening 19, as desired. As the chicks become older, and consequently larger, a block, not shown in the drawing, may be placed under the lower margin of the shell 11 to raise it higher above the bottom 10. The guard 17, which is carried by the bottom 10, is suffi- 110

ciently high to permit the stack 15 to telescope thereinto and consequently when the shell 11 is raised, as described, the guard still serves its function. When the brooder 5 is stored away, the housing portion 4 may be telescoped on portion 2 to make it more compact.

I claim:

1. In a brooder, a hover including two telescopic portions, one having a bottom and the other a top, said portions being disposed to permit ingress of air to within the hover, and means for snugly engaging the chicks within the hover.
- 15 2. In a brooder, a hover including two cylindrical shells adapted to telescope and rotate one with respect to the other; and one having a bottom and the other a top, said shells being disposed to permit ingress 20 of air to within the hover and having openings in the walls thereof adapted to register with each other, and means providing for egress of air from within said shells.
- 25 3. In a brooder, a hover comprising in combination, a cylindrical shell provided with a bottom, a second cylindrical shell provided with a top, adapted to telescope said first mentioned cylindrical shell with a space therebetween and having a plurality 30 of recesses at its lower margin, said cylindrical shells having openings adapted to register and permit access to and from the same, a stack carried by said first mentioned shell concentric therewith, a guard about said stack, and a blanket carried by said second mentioned shell.
- 35 4. In a brooder, a hover comprising in

combination, a cylindrical shell provided with a bottom, a second cylindrical shell provided with a top, adapted to telescope 40 said first mentioned cylindrical shell with a space therebetween and having a plurality of recesses in its lower margin, a guard carried by the said bottom of said first mentioned shell concentric therewith, and a 45 stack carried by said second mentioned shell concentric therewith and adapted to telescope scope with said guard.

5. In a brooder, a hover comprising in combination, a cylindrical shell provided with a bottom, a second cylindrical shell provided with a top, adapted to telescope 50 said first mentioned cylindrical shell with a space therebetween and having a plurality of recesses in its lower margin, a stack carried by said second mentioned shell concentric therewith, and a blanket carried by said second mentioned shell.

6. A brooder comprising in combination, a housing including a box-like portion having an opening in one side and a second box-like portion adapted to telescope said first mentioned box-like portion with the said opening exposed thereinto, and a hover 60 adapted to be carried by said first mentioned box-like portion and having an opening adapted to be positioned at the said opening in the latter.

In testimony whereof I affix my signature in presence of two witnesses.

JAMES W. MORRIS.
